UNITED STATES PATENT OFFICE

158,384

BULK MATERIALS CARRIER

Roderick M. Iversen, Lafayette, Calif., assignor to
Western Iron and Body Works, Oakland, Calif.,
a partnership

Application March 30, 1948, Serial No. 145,444

Term of patent 14 years

(Cl. D14—3)

To the Commissioner of Patents:

Be it known that I, Roderick M. Iversen, a citizen of the United States of America, residing at Lafayette, county of Alameda, State of California, have invented a new, original, and ornamental Design for a Bulk Materials Carrier, of which the following is a specification, reference being had to the accompanying drawing, in which:

Figure 1 is a top plan view of a bulk materials carrier, showing my new design;

Figure 2 is a side elevation of the subject matter of Figure 1; and

Figure 3 is a rear end elevation of the same.

The characteristic features of my design reside in the portions shown by means of full lines in the drawing.

I claim:

The ornamental design for a bulk materials carrier, substantially as shown and described.

RODERICK M. IVERSEN.
